UNITED STATES PATENT OFFICE

ALBERT J. BAYLES, OF MAYWOOD, ILLINOIS, ASSIGNOR TO SOLAR-STURGES MFG. CO.,
OF BELLWOOD, ILLINOIS, A CORPORATION OF ILLINOIS

RECEPTACLE AND METHOD OF MAKING SAME

Application filed September 12, 1927. Serial No. 219,154.

This invention relates to a receptacle and the method of making the same, and more particularly to a milk can or similar container wherein a unitary portion affording 5 a seamless neck and breast is secured to the body portion to provide a smooth interior and a rigid strong joint affording at its top an outwardly extending peripheral shoulder which serves as a stop shoulder for pos- 10 titioning a bumper band.

In the past many types of joints have been employed to unite the breast and body portions of a receptacle, and though these joints, in many cases, were sufficiently strong, they 15 have proved objectionable due to the undesirably large expenditure of time, labor, and materials, necessitated by their construction.

This invention seeks to overcome the above noted objections in the provision of a receptacle utilizing a one-piece neck and breast, wherein the body portion is joined to the breast portion quickly and easily and the joint therebetween, which may be electrically welded, is of double thickness and thereby 25 reinforced efficiently and very economically.

Another object of this invention is to provide means for reinforcing the joint between the two portions of the receptacle with an obvious saving of time and material.

Other and further important objects of this invention will be apparent from the disclosures in the specification and the accompanying drawings.

The invention in a preferred form I have 35 illustrated in the drawings and hereinafter more fully described.

On the drawings:

Figure 1 is a view in elevation of a receptacle embodying features of and constructed 40 in accordance with the present invention.

Figure 2 is an enlarged fragmentary vertical section through the upper portion of the receptacle shown in Figure 1.

As shown in the drawings:

In the illustrated embodiment of this invention there is shown a milk can, designated in general by the reference numeral 1, which is formed by joining a body portion 2 and 50 a breast portion 3. The neck 3' of the can

or receptacle 1, is integral with the breast portion 3.

Novel means have been provided to unite the breast and the body portions of the receptacle. The breast portion 3 is provided 55 with an offset rim 4 to telescopically receive and engage therein the upper extremity of the body portion 2, the body portion being scarfed as at 5 to fit tightly against the breast portion.

The rim 4 is preferably electrically welded to the upper margin of the body portion 2, whereby a tight and rigid joint is formed, the metal at the joint being of double thickness thus forming a peripheral outer shoulder at the top of the joint which affords a 60 stop for the bumper band 7. When the joint is electrically welded and the receptacle is tinned, a smooth interior sanitary joint is 65 thereby formed.

It is to be noted that the breast portion 3 is provided with a marginal portion 6 disposed between the rim 4 and the sloping part of the breast portion and which is cylindrical and substantially a continuation of the body portion 2. After the breast and body portions are joined as hereinabove explained the bumper or reinforcing band 7 is engaged around the exterior of the marginal portion 6. This bumper band 7 may be put on in 70 any desired manner, such as pressed on, welded, shrunk, rolled, etc., but which is preferably forced on and later rolled or welded, for further strengthening the joint. The band 7, as shown in Figure 2, abuts the shoulder 75 formed by the rim 4, whereby the band is held in place and can never drop down even though the bumper band becomes somewhat loosened from the exterior surface of the breast portion.

It is, of course, understood that after the parts are assembled in the manner previously described, the can is tinned over the interior and exterior surfaces to enhance its appearance and adapt the same to be easily and thoroughly cleansed. The exterior tinning serves to seal the bumper band on the can making the joints thoroughly sanitary.

From the foregoing it is apparent that I have provided a milk can or similar container 100

the breast and body portions of which are united by a simple inexpensive joint and reinforced by a bumper band readily and easily applied without detracting from the appearance of the container.

I am aware that many changes may be made and numerous details of construction may be varied through a wide range without departing from the principles of this invention and I, therefore, do not purpose limiting the patent granted hereon otherwise than necessitated by the prior art.

I claim as my invention:

1. In a receptacle, a smooth-walled body portion, a breast portion having a margin of substantially the same size and contour as said body portion, an outwardly offset rim on said margin providing an outer shoulder and telescopically engaged over and secured to the upper part of said body portion, and a bumper band around said margin entirely above said rim and in abutment with said shoulder.

2. In a receptacle, a body portion, a breast portion, an outwardly offset rim on one of said portions telescopically engaged over and secured to the adjacent end of the other of said portions, said rim providing a shoulder abutted on the inner side thereof by said other portion, and a bumper band around one of said portions only and having an edge thereof abutting the outer side of said shoulder.

In testimony whereof I have hereunto subscribed my name at Chicago, Cook County, Illinois.

ALBERT J. BAYLES.
